Oakland, Calif.

Application June 2, 1944, Serial No. 538,370

2 Claims. (246—452)

1

The present invention relates to railway track switches of the type operated by remotely controlled power machines.

In track switches of this type, the switch points are shifted from one position to the other by a power actuated switch machine which has incorporated in it a locking mechanism designed to prevent accidental movement of the switch points after they have completed their authorized shifting movement. The locking mechanism commonly comprises cooperating sliding bars having interfitting lugs and notches, one bar being moved by the switch machine and the other bar being directly connected with and moved by the switch points.

Interstate Commerce Commission regulations provide that the switch shall be so maintained that it cannot be locked unless the switch points are within one quarter of an inch of their final position against the side of the track or stock rails. Inability of the locking mechanism to function automatically gives an appropriate warning. Normal test procedure involves placing a quarter inch rod between the switch point and the ball of the stock rail while the switch machine is functioning to throw the switch, and under these conditions the locking mechanism must not be able to complete its locking function.

The test procedure described above imposes excessive strain on the switch machine and the connections between it and the switch points, and causes wear and deterioration of the interfitting parts of the locking mechanism. When the moving switch point meets the quarter inch obstruction placed between it and the ball of the rail, the lower portion of the switch point continues to move, the switch points being sufficiently thin and resilient to permit some twisting. As a result, the locking mechanism, which is connected with the lower portions of the switch points, is moved almost into position to enable the lugs of the slide bar to engage the notches of the locking rod. In other words, although the switch points are stopped at a distance of one quarter of an inch away from the ball of the rail, the lack of alignment of the lugs and notches of the locking mechanism is much less than one quarter of an inch, and is so small as to produce a tendency for the locking mechanism to force said lugs and notches into engagement. As a result, the edges of the locking lugs and notches become cut and rounded off, and after a comparatively small number of test operations under such conditions said locking lugs and notches become worn to such an extent that repair or

2

replacement is required. Operation of the switch points against a test obstruction as described above, or against an accidental obstruction which may lodge between the switch points and the stock rails, also results in undue stresses in the parts of the switch machine and in the connections between it and the switch points.

The principal object of the present invention is to provide a resilient connection between the operating rod of the switch machine and the tie rod of the switch points, which allows the switch machine to complete its operation except for its locking function, even though there may be a small obstruction between the switch points and the stock rails, without unduly stressing the operating parts and connections of the switch machine.

A corollary object is to prevent twisting of the switch points in the event of obstruction as described above, and thereby to cause the interfitting parts of the locking mechanism to remain so far out of line that they cannot be forced into locking engagement, and thereby to prevent undue wear and deterioration of the edges of said interfitting parts.

Another object of the invention is to provide a resilient connection between the switch machine and the switch points in which the extent of resilience or cushioning movement is limited positively by adjustable rigid stops, so that safe operation of the switch is not dependent upon the integrity of the resilient members. Other objects and advantages of the invention will become apparent from the following description of a preferred embodiment thereof, which should be read with the understanding that changes within the scope of the claims hereto appended may be made in the form, construction and arrangement of the several parts herein described and illustrated.

In the accompanying drawing,
Fig. 1 is a plan view of a track switch operated by a switch machine through our improved resilient connection. Only those parts of the switch machine are shown which are necessary to an understanding of the function and purpose of our invention.

Fig. 2 is a detailed view partly in section of the interfitting parts of the locking mechanism.

Fig. 3 is a detailed view partly in section of our improved resilient connection.

Referring in more detail to the drawing, the reference numerals 5 designate the track or stock rails of a railway switch, and 6 are the movable switch points, the latter being connected to

gether by a main tie rod 7 and a front tie rod 8. The switch machine 9 has a slide bar 10 and a cam 11 connected with said bar by a lug 12. The cam 11 oscillates on a vertical spindle from which extends a lever 13. The operating rod 14 is connected with the lever 13 and with the tie rod 7 of the switch points by a connecting bracket 15 which is bolted to said tie rod.

The locking mechanism of the switch machine comprises two lock rods 16 forming adjustable extensions of the front tie rod 8 and provided with notches 17. The slide bar 10, operating at right angles to the lock rods 16, is provided with lugs or dogs 18 to engage the notches 17 and thereby to prevent movement of the front rod 8 and the switch points. The operation of the switch machine is such that the slide bar 10 is first moved to carry the lugs 18 out of engagement with the notches 17, then to operate the rod 14 to throw the switch points, and finally to move the slide bar 10 to bring one of the lugs 18 into engagement with the appropriate notch 17. So much is the usual construction and operation of a power operated track switch.

Our invention involves specifically the connecting bracket 15, which has a horizontal flange 19 adapted to be bolted or riveted to the tie rod 7 as at 20. The bracket 15 has a bore extending through it, the diameter of the end portions thereof being greater, as shown at 21, than is the diameter of the central portion 22.

The operating rod 14 of the switch machine extends through the bore of the bracket 15, and is threaded for a considerable distance on either side of said bracket. Spaced collars 23 are threaded upon the rod 14 on either side of the bracket 15 and are spaced slightly from the side faces thereof. Lock nuts 24 secure the collars 23 in position. Helical springs 25 are housed within the enlarged end portions 21 of the bore of the bracket 15 and are compressed between the collars 23 and the shoulders 26 at the inner ends of said enlarged portions. A protecting sleeve 27 surrounds the rod 14 between the collars 23 to prevent damage to the threads due to movement between the rod and the bracket 15.

The springs 25 are so proportioned, and the collars 23 are so positioned, that the maximum movement of the rod 14 through the bracket 15, in either direction from its normal balanced position, is slightly less than the minimum prohibited distance between switch point and stock rail. For example, when said minimum prohibited distance is one quarter inch, as determined by the thickness of the test obstruction described above, the distance through which the rod 14 will move through the bracket 15 is about three sixteenths of an inch. Therefore, when the switch is thrown against the test obstruction, the rod 14 continues to move for three sixteenths of an inch, compressing one of the springs 25 before materially increasing the stresses in the operating connections, and before any twisting occurs in the switch points. The one sixteenth of an inch difference between the width of the test obstruction and the permitted compression of the cushioning spring

25 is so small as to be easily absorbed in the resilience of the various connected parts, without producing undue stress therein. As a result, the switch points are not twisted appreciably, and the front rod 8 and lock rod 16 are not moved appreciably after the test obstruction is encountered, and the lugs and notches of the locking mechanism remain substantially one quarter of an inch out of alignment, so that the slide bar 10 cannot be forced home, and the edges of said lugs and notches are preserved from wear and deterioration.

The cushioning springs 25 are sufficiently strong to keep the switch points tight against the stock rails. In practice, the parts are so adjusted that in normal operation the operating rod 14 moves about one sixteenth of an inch against the compression of one of the springs 25 after the switch point has contacted the stop rail.

If one or both of the cushioning springs 25 should break, the collars 23 would act as positive stops to limit the movement of the rod 14 through the bracket 15 to less than one quarter of an inch, so that even in the event of such spring failure the switch points could not remain open by a sufficient amount to be dangerous.

We claim:

1. In a power operated railway track switch, fixed track rails, movable switch points, a switch machine having a movable operating member and a movable locking member, a resilient connection between said operating member and the switch points, a member rigidly connected with and moved by said points, interengaging locking means carried by said rigidly connected member and said locking member to lock said points at either limit of their movement, said locking means being inoperative when the separation between either point and the corresponding rail exceeds a predetermined minimum distance, and means for limiting the relative movement at said resilient connection between said operating member and the switch points to an amount no greater than said predetermined minimum separation between said points and the track rails.

2. In a power operated railway track switch, fixed track rails, movable switch points, separate operating and locking tie rods connecting said points, a switch machine having a movable operating member and a movable locking member, a resilient connection between said operating member and said operating tie rod, a member connected with said locking tie rod having means cooperating with the locking member of said machine to lock the switch points at either limit of their movement, said locking means being inoperative when the separation between either point and the corresponding rail exceeds a predetermined minimum distance, and means for limiting the relative movement at said resilient connection between said operating member and said operating tie rod to an amount no greater than said predetermined minimum separation between said points and the track rails.
